COVER FOR GUN SIGHTS

Filed Feb. 5, 1924

FIG. 1.

FIG. 2.

INVENTOR
Charles L. Paulus
Robert Kauch
BY

Robert H Young ATTORNEY

UNITED STATES PATENT OFFICE.

CHARLES L. PAULUS AND ROBERT KAUCH, OF DAYTON, OHIO.

COVER FOR GUN SIGHTS.

Application filed February 5, 1924. Serial No. 690,770.

This invention relates to a cover for gun sights used on aircraft, and is designed to keep the front lens or cover glass of the sight clear of a coating of oil, oil vapor, mist, water, or the like, which is otherwise deposited by the slipstream when the airplane is in flight, or more particularly when it is being tuned up preparatory to taking off, at which time there is usually surplus water and oil thrown in the form of a spray by the propeller.

One of the principal objects of the invention is to provide a cover of a relatively simple construction having a sealing fit on the end of the sight tube and adapted for rotation on an axis parallel to the axis of the sight tube out of range or vision through the tube and into a position where the action of the slipstream does not have any tendency to close the cover nor to place any undue load on its operating means.

Another object is to provide in connection with the cover a means for yieldingly holding it in either of the two positions which it occupies.

In the drawing illustrating the invention,

Fig. 1 is a side view partly in section, and partly in elevation of a gun sight equipped with a cover of the present invention. An intermediate portion of the sight tube and cover-operating rod is broken away.

Fig. 2 is an end view of the tube with the cover in place thereon.

The invention is herein described as applied to gun sights, although it will appear in the course of the following description that the various features of the cover adapt it for more or less general application to sighting devices wherever it is desired to provide similar protection for lenses or cover glasses.

The gun sight tube 1 which is mounted in the plane usually at some point where it is subject to the slipstream has an eye piece 2 of suitably resilient material at one end and is provided with a lens or cover glass 3 in its forward end. Other lenses forming an optical system, it is understood will be included in the intermediate portion of the tube. The lens 3 is held in place in the end of the tube by a retaining ring 4 threaded or otherwise suitably held upon the end of the tube. This ring has its outer face bevelled to provide a bevelled on tapered seat 5.

A sheet metal cover 6 of a concave form has

an annular lip 7 of a similar inclination to the seat 5 to fit snugly and with a sealing fit thereon when the cover is in place. The cover is riveted as at 8 to the forward end 9 of an operating rod 10 extending lengthwise of the tube 1 to a point readily accessible to the observer at the inner end of the tube. The rod 10 is received in a bearing 11 provided in the retaining ring 4 on one side of the tube 1. It is also received in a bearing 12 provided in a ring 13 fitted on the tube 1 near the eye-piece 2. The bearings enable rotation of the rod with the cover on an axis parallel with the axis of the tube. The rod 10 is bent outwardly as shown at 14 to provide an operating arm for manually rotating the cover 6 to and from its position covering the end of the tube.

A compression spring 15 encircles the rod 10 and abuts at its opposite ends the bearing 11 and a washer 16 held in place on the rod 10 by a pin 17 so that the cover 6 is yieldingly urged inwardly toward more intimate contact with the seat 5 sealing the end of the tube and preventing accidental displacement. The spring also provides a frictional drag on the movement of the cover which serves to retain it in either of its adjusted positions, as it is important that the cover should not swing into the range of vision through the tube when an observation is being made. In this connection, it might also be noted that in the opening of the cover the bevelled end of the retaining ring 4 causes the cover to move bodily outwardly in riding over it and then moves inwardly at the limit of its movement. Similarly when the cover swings back into place it moves bodily outwardly in riding back over the bevelled end of the ring 4 and then rides inwardly into its fully closed position, aided somewhat by the action of the spring 15. This feature coupled with the fact that the spring 15 gives a sealing fit of the cover on the tube as it urges the cover inwardly, prevents accidental movement of the cover into or out of place.

The sight cover is normally in the position shown in Fig. 1 and just before aiming the guns, the rod 10 is turned to move the cover so that it will not interfere with vision through the sight. The cover is then maintained in this position by the spring 15 until after the guns have been fired, at which time the rod 10 is again turned to replace the

cover. The spring serves to draw the cover into snug sealing contact covering the end of the tube.

We claim:—

- 5 1. In a sight device, a tube having a front lens or cover glass in the end thereof, a tapered seat at the outer end of said tube in front of said cover glass, a cover for the end of said tube having a face thereof to engage said tapered seat to seal the end of said tube, said cover being rotatable edgewise to a position out of range of vision through the tube and being caused to move outwardly and inwardly in moving from open to closed position or vice versa in riding over said tapered seat, and spring means normally urging said cover inwardly.
- 10 2. In a sight device, a tube having a front lens or cover glass in the end thereof, a securing member for said glass forming a tapered seat at the forward end of said tube in front of said cover glass, a concave cover slidable over said seat edgewise from a position out of range of sight through the tube to a position engaging said seat and covering

the end of said tube, a manually rotatable rod for operating said cover to swing it into and out of position covering the end of said tube, and spring means for yieldingly urging said cover inwardly.

- 15 3. In a sight device for aircraft, a tube having a front lens or cover glass in the end thereof, a cover for the end of said tube to protect said lens, a bearing on the side of said tube, a rod rotatably received in said bearing extending lengthwise alongside the tube having one end connected with said cover and its other end bent outwardly to provide an arm for manually operating said cover, and a spring acting between said bearing and said rod to urge said cover yieldingly inwardly toward the end of said tube to effect a sealing contact when the tube is covered and to hold said cover in either of its adjusted positions covering and uncovering the tube.

In testimony whereof we affix our signatures.

CHARLES L. PAULUS.
ROBERT KAUCH.
